G. L. THOM.

PUNCH.

APPLICATION FILED FEB. 10, 1913.

1,098,696.

Patented June 2, 1914.

Fig. 2.

UNITED STATES PATENT OFFICE.

GEORGE L. THOM, OF BROOKLYN, NEW YORK, ASSIGNOR TO WILLIAM WALLACE
MC LAURIN, OF BROOKFIELD, MASSACHUSETTS.

PUNCH.

1,098,696.

Specification of Letters Patent. Patented June 2, 1914.

Application filed February 10, 1913. Serial No. 747,441.

To all whom it may concern:

Be it known that I, GEORGE L. THOM, a citizen of the United States, residing at Brooklyn, in the county of Kings and State 5 of New York, have invented certain new and useful Improvements in Punches; and I do hereby declare the following to be a full, clear, and exact description of the invention, such as will enable others skilled 10 in the art to which it appertains to make and use the same.

This invention is a punch and has for an object to provide a number of dies carried in a single outfit comprising a pair of oper- 15 able handles, a die member and a piece against which said die member is adapted to bear after penetrating the article to be punched.

Figure 1 is a sectional view of a punch 20 constructed in accordance with my invention having parts thereof in elevation. Fig. 2 is a series of views showing the die members in section. Fig. 3 shows the die members in elevation. Fig. 4 is a horizontal 25 sectional view showing the cam faces of the several die members. Fig. 5 is a side elevation of my device. Fig. 6 is a side elevation of the punch showing the parallel bars arched for a portion of their lengths ad- 30 jacent the anvil and die members. Fig. 7 is a modified form of an anvil to produce a circumferential movement with respect to the die members.

Referring more specifically to the drawings 35 10 indicates a pair of handles pivoted to one another as at 11 and to parallel members as at 12. These parallel members are designated by the numerals 13 and 14 and as shown have the forward ends of the handles 10 secured thereto to permit the swivel movement between these members 13 and 14 and the handles 10 while the fastening means 12 adjacent the rear ends of these members pass through slots to permit sufficient move- 40 45 ment when the handles are swung together. The member 13 is provided with the head 15 in which is mounted a plate 16 which may be of zinc, lead, or any other suitable material. The member 14 is provided with the head 17 50 having the flange 18 thereabout and having pins 19 secured thereto as shown.

The numeral 20 indicates a screw for holding several parts to the head 17 to be hereinafter described. A series of annular

die members 21, 22, 23 and 24 are placed in 55 the cupped head and are provided with key- ways to accommodate the pins 19 so as to permit vertical movement of the die mem- bers but to restrict circumferential move- 60 ment thereof. Any one of the four die 65 members may be disposed to present its cutting edge beyond the remaining three and this is accomplished by means of a member 25 having a central portion to receive the bolt 20 after passing through a plug 26 65 which plug is held against rotation by its engagement with one of the pins 19. The ends of the bars of the member 25 termin- 70 ate in thumb pieces 27 by which this mem- ber may be manipulated and the ends of 75 this member extend through the slots 28 in the wall 18 to limit the movement of the member 25 in both directions. To assist in determining which one of the several die members is projected by the movement of 80 the member 25, a series of index figures 29 may be formed in the wall 18 adjacent to the slots 28. Each of the several die mem- bers may be made of single pieces of ma- 85 terial and slotted or they may be made of two pieces of metal in view of the difficulty in treating tool steel. In any event cams 90 30 are formed on each of the die members so that when the several dies are assembled the cams of the several dies are disposed in 95 advance of the adjacent one so that the arms of the member 25 will engage one or another of the pairs of cams in any position within its movement. The upper wall of each slot conforms with the lower one so as to return 90 the die member into inoperative position when that particular die is not desired for usage and in the event of each of the die members being made of two pieces of ma- 95 terial fastened to one another in any de- sired means, the numeral 31 indicates the upper piece of each of the dies.

The parallel bars 13 and 14 are shown arched for a portion of their length as in Fig. 6 to permit the gathering of a quantity 100 of material in said arched portions when it is desired to punch a piece of fabric at a distance from the edge thereof.

In the modification shown in Fig. 7, the head 32 has a trunnion 33 which is mounted 105 in a bearing 34 formed in the socket 35 car- ried by the bar 13. A ratchet 36 is formed on the head 32, and a pawl 37 which receives

its movement by its fastening with the rivet 12 engages a ratchet to set up a partially rotary movement to the head 32 at each manipulation of the handles. This pawl may 5 be made of resilient material to eliminate the use of an additional spring, or the spring 38 may be used to maintain the engagement of said pawl and ratchet.

Further modifications may be made within 10 in the scope of this invention such as modified means in moving the several die members with respect to one another as by cam slots in the several die members and lugs carried by the adjacent die members to engage said cam slots. 15

Having thus described my invention, I claim:

1. In a punch, movable members, an anvil carried by one of said members, a plurality 20 of dies carried by the other of said members and means to project any one of said dies beyond the others.

2. In a punch, movable members, an anvil carried by one of said members, a plurality 25 of various sized dies nested one in the other carried by the other of said members each of said dies having movement with respect to its supporting medium and means carried by the supporting medium for projecting 30 any one of said dies beyond the others.

3. In a punch, movable members, an anvil carried by one of said members, a plurality of dies carried by the other of said members, each of said dies having a limited movement 35 with respect to its supporting medium and means carried by the supporting medium for

extending any one of the several dies beyond the others.

4. In a punch, a supporting member, a plurality of die members of different diameters, said die members being nested each of said die members having an irregular surface, said irregular surfaces of said die members having stepped relation with each other and means carried by said supporting member 40 for engaging said irregular surfaces to extend any one of said die members beyond the others. 45

5. In a punch, movable members, a plurality of dies carried by one of said members, an anvil carried by the other of said members, and means for moving said anvil circumferentially upon manipulation of the punch. 50

6. In a punch of the class described, a supporting member having a cup shaped 55 socket formed therein, a plurality of die members of different diameters disposed therein, means carried by said supporting member to engage said die members to prevent rotation thereof, each of said die members having a cam face formed thereon, and rotatable means carried by said supporting means for engagement with said cam faces formed on said die members to extend any 60 one of said die members beyond the others. 65

In testimony whereof I affix my signature in presence of two witnesses.

GEORGE L. THOM.

Witnesses:

MAE PERRY,

HELEN ANNA VAN ETEN.
